[57] CLAIM

The ornamental design for a Christmas tree garland hook, as shown and described.

DESCRIPTION

FIG. 1 is a front elevational view of a Christmas tree garland hook embodying my new design;

FIG. 2 is a side elevational view thereof;

FIG. 3 is a rear elevational view thereof;

FIG. 4 is a side elevational view of the opposite side from that depicted in FIG. 2;

FIG. 5 is a top plan view thereof;

FIG. 6 is a bottom plan view thereof;

FIG. 7 is a front elevational view of a second embodiment of the Christmas tree garland hook design of my invention;

FIG. 8 is a side elevational view of the embodiment of FIG. 7;

FIG. 9 is a rear elevational view of the embodiment of FIG. 7;

FIG. 10 is a side elevational view of the opposite side from that depicted in FIG. 8;

FIG. 11 is a top plan view of the embodiment of FIG. 7; and

FIG. 12 is a bottom plan view of the embodiment of FIG. 7.
